UNITED STATES PATENT OFFICE.

CARL E. BROWN, OF COLUMBUS, OHIO.

OIL-BURNER.

1,281,130.

Specification of Letters Patent.

Patented Oct. 8, 1918.

Application filed January 2, 1918. Serial No. 210,028.

To all whom it may concern:

Be it known that I, CARL E. BROWN, a citizen of the United States, residing at Columbus, in the county of Franklin and State of Ohio, have invented a new and useful Oil-Burner, of which the following is a specification.

The device forming the subject matter of this application is a burner of that general type wherein a U-shaped conduit is employed, and the invention aims to provide a simple but effective structure whereby the conduit may be raised and lowered, and be held at adjusted heights, thereby to adapt the structure for fire boxes of large or small dimensions.

A typical embodiment of the invention, only, is shown in the drawings, and it is to be understood, that, within the scope of what is claimed, changes such as a mechanic might make, may be resorted to without departing from the spirit of the invention.

In the accompanying drawings:—

Figure 1 shows in side elevation, a burner constructed in accordance with the present invention;

Fig. 2 is a section taken approximately on the line 2—2 of Fig. 1;

Fig. 3 is a section taken approximately on the line 3—3 of Fig. 2;

Fig. 4 is an elevation of the bracket;

Fig. 5 is an elevation of the standard.

In the accompanying drawings, the numeral 1 denotes a U-shaped conduit comprising an upper arm 2 and a lower arm 3. At 4 there appears any suitable means whereby oil may be supplied to the upper arm 2. The upper arm 2 carries flame-spreaders 5 and in the lower arm 3 there are burner orifices 6 disposed below the flame spreaders. The lower arm 3 may carry a priming pan 7.

The invention contemplates the provision of a vertically extensible and contractible supporting means for the structure above described, and with this end in view, two like structures are provided, but one of which will be described in detail.

Oppositely disposed brackets 8 are provided, each bracket including a body 9 having a concaved seat 10, an outwardly extended arm 11 at the lower end of the body, and a finger 12 depending from the arm 11 and disposed, preferably, at an obtuse angle thereto. Securing devices, such as bolts 14, 55 connect the body portions 9 of the brackets 8, above and below the seats 10. The lower arm 3 of the conduit 1 thus is clamped and held in the seats.

The invention comprises a pair of standards 15, each including an upright 16 and a laterally extended foot 17 disposed at an obtuse angle to the upright. A longitudinal groove 19 is formed in the inner face of the upright 16 and receives, slidably, a rib 20 60 formed on the forward face of the finger 12 of the bracket 8. Openings 18 are fashioned in the upright 16. A single securing device 21, which may be a bolt, is mounted in the finger 12 of the bracket and is adapted to be mounted in any of the openings 18 of the upright 16. The construction, obviously, is such that the brackets 8 may be raised and lowered with regard to the respective standards, and be held in any positions to which they may have been adjusted. Since the bracket 8 includes the rib 20 received in the groove 19 of the standard 15, the parts 15 and 8 will remain in alinement, even though they are held together by the single bolt 21. 70

Generally stated, there is disclosed in this application, a simple but efficient means whereby the conduit 1 may be held at such adjusted heights as the exigencies of the proposed use may demand.

I claim:—

1. In a device of the class described, a U-shaped conduit comprising an upper fuel-receiving arm, and a lower arm having a burner orifice; oppositely disposed brackets engaging the lower arm; means for connecting the brackets; standards; and means for connecting the brackets with the standards for vertical adjustment.
2. In a device of the class described, a

U-shaped conduit comprising an upper fuel-receiving arm, and a lower arm having a burner orifice; a bracket structure engaged with the lower arm; standards assembled with the bracket structure by tongue-and-groove joints for vertical sliding adjustment; and means for connecting the bracket structure with the standards at adjusted points.

In testimony that I claim the foregoing 10 as my own, I have hereto affixed my signature in the presence of two witnesses.

CARL E. BROWN.
